FIG. 3.

UNITED STATES PATENT OFFICE.

WILLIAM S. BRYANT, OF BOSTON, MASSACHUSETTS.

FLOATING PUMP.

SPECIFICATION forming part of Letters Patent No. 643,863, dated February 20, 1900.

Application filed May 24, 1898. Serial No. 681,591. (No model.)

To all whom it may concern:

Be it known that I, WILLIAM S. BRYANT, a citizen of the United States, residing in Boston, in the county of Suffolk and State of 5 Massachusetts, have invented an Improvement in Floating Pumps, of which the following description, in connection with the accompanying drawings, is a specification, like letters on the drawings representing like 10 parts.

This invention relates to an apparatus for utilizing wave motion for power purposes; and it consists of an apparatus of a construction as will be described, and pointed out in 15 the claims at the end of this specification.

Figure 1 is a vertical section, with parts broken away, of a floating pump embodying this invention; Fig. 2 a like section of a modification to be referred to; and Fig. 3 a view 20 like Fig. 1, representing the float in the trough of the sea.

Referring to the drawings, A represents a tube or pipe constituting the movable cylinder of my improved floating pump, which 25 is provided with a stationary water-piston, (indicated by the broken line a,) the said water being admitted up into the cylinder A, as herein shown, through the open lower end. The cylinder A is provided with a head a², and the walls of the cylinder may be extended 30 beyond the head a² and closed by a cap or head a³, forming an air-reservoir or accumulating-chamber a⁴. The cylinder A is moved vertically by motion of the waves, and this 35 may be accomplished by securing the said cylinder to a suitable float or buoy A', which may be of any suitable form. The cylinder A when moved upward is designed to be filled with air above the water-piston therein, which 40 may be effected by providing the said cylinder with an air-inlet port a⁵ in its head a², with which communicates an air-inlet pipe a⁶, shown as extended up through the air-reservoir a⁴ and communicating with the atmosphere. The air-inlet port a⁵ has coöperating 45 with it a valve, represented as a flap-valve a⁷, which is designed to open to admit air into the cylinder on its up movement and to be closed by the pressure of air in said cylinder 50 on its down movement. The cylinder A is further provided with an air-outlet port a⁸, through which the air in the cylinder A is

forced out therefrom on the down movement of the said cylinder, and this port has coöperating with it a valve, which is represented 55 as a flap-valve a¹⁰ and which is opened by the air forced out of the cylinder on the down movement and is closed on the up movement thereof, thereby permitting the passage of the compressed air out of the cylinder, but 60 preventing the return of said compressed air. The air forced out of the cylinder may be stored under pressure in the reservoir or accumulating-chamber a⁴ and utilized for power purposes at the floating pump, and in the 65 present instance I have represented in Fig. 2 a whistle b²⁵ as operated by the air in the reservoir when the said air has reached a pressure sufficient to lift a valve b⁵ against the action of a spring b⁶, the said valve controlling the outlet-port b⁴ for the reservoir. The reservoir a⁴ in Fig. 2 is also shown as 70 communicating with the air-chamber a¹⁸ of the float A' through ports a¹⁴, which serves to increase the size of the air-reservoir. 75

In Fig. 1 the reservoir a⁴ is shown as provided with an outlet-pipe b⁸, provided with a flexible extension b⁹, which may be of any desired or required length and may convey the compressed air to the shore or other place 80 where it is to be used or to a second storage-tank. The outlet-pipe b⁸ may connect directly with the port a⁸ and be provided with the automatic valve a¹⁰.

The cylinder A may be provided with a substantially-conical deflector b, having its apex coöperating with the port or opening a⁸ to direct the compressed air through said port and into the accumulating-chamber a⁴. The deflector b may be provided near its lower end 90 with one or more openings b', through which the air is admitted to the cylinder A.

In operation air is drawn into the cylinder A through the inlet-pipe a⁶ on the up movement of the buoy or float effected by the 95 waves and represented by Fig. 1, and on the down movement of the float or buoy (represented by Fig. 3) the air in the cylinder is forced through the port a⁸ into the chamber a⁴ and is prevented from passing back into 100 the cylinder on the next up movement of the buoy by the valve a¹⁰. The air-inlet is closed by the valve a⁷, which is seated by the pressure of air in the cylinder A as the said air is

forced into the chamber a^4 . The air forced into the chamber a^4 may be accumulated therein until the desired pressure has been attained, and the compressed air in the accumulating-chamber may be used at the accumulator, passing out therefrom through the port b^4 , (see Fig. 2,) controlled by the valve b^5 , which is seated by the spring b^6 , which latter is adjusted so as to require a predetermined pressure of air to open the valve and permit the escape of the compressed air from the accumulator. The compressed air escaping from the accumulator operates the whistle b^{25} , which may be of any suitable construction.

In order to prevent the accumulating-chamber becoming filled with water, which may be carried into the said chamber with the air, the said chamber may be provided with an automatically-operated valve, which controls a port b^{12} in the cylinder-head a^2 . In the present instance the valve referred to is shown as a ball b^{13} on a stem attached to a pivoted lever b^{14} , provided with a ball or float b^{15} , which latter is raised by the accumulated water in the chamber a^4 and opens the port b^{12} , so as to permit the water to run back into the chamber a^3 . The buoy may be anchored in any suitable or usual manner, as by chains b^{20} .

In practice the tube or pipe A is made of a length sufficient to carry its lower open end below the level of water which is affected by wave motion, and consequently the lower end of the tube or pipe is surrounded by quiescent water, and therefore the column of water confined in the said tube or pipe is practically stationary, because it is not influenced by motion of the waves, which is confined to the surface.

I claim—

1. In a floating pump, the combination with

a substantially-long tube or pipe provided with a water-inlet at or near its lower end and separated by a partition wall or head to form an air-reservoir above and a water-chamber below the same, an air-inlet pipe extended through the air-reservoir and opening into the said water-chamber, a valve controlling the passage of air into the water-chamber, a separate port or opening through said partition-wall from said water-chamber into said air-reservoir, a valve coöperating with said port or opening, and an outlet-pipe for the said reservoir to conduct the compressed air in the reservoir directly out therefrom and provided with a flexible extension, substantially as described.

2. The combination with a floating pump provided with an air-cylinder immersed in water to form a stationary water-piston therein and responsive to wave motion of a deflector in the air-cylinder coöperating with the air-outlet port for said cylinder, substantially as described.

3. The combination with a floating pump having an air-cylinder immersed in water to form a stationary water-piston, and provided with an air-inlet port and with an air-outlet port, valves coöperating with said ports, an air-reservoir communicating with the air-cylinder through the outlet-port, a second port connecting said air-cylinder and air-reservoir, a valve coöperating with said second port, and a float in the said reservoir to operate said valve, substantially as described.

In testimony whereof I have signed my name to this specification in the presence of two subscribing witnesses.

WILLIAM S. BRYANT.
